UNITED STATES PATENT OFFICE.

ANTON OHNEMUS, OF QUINCY, ILLINOIS.

DESIGN FOR A HEATING-STOVE.

SPECIFICATION forming part of Design No. 26,474, dated December 29, 1896.

Application filed March 2, 1896. Serial No. 581,594. Term of patent 7 years.

To all whom it may concern:

Be it known that I, ANTON OHNEMUS, a citizen of the United States, residing at Quincy, in the county of Adams, State of Illinois, have invented and produced a new and original Design for Stoves, of which the following is a specification, reference being had therein to the accompanying drawing.

The drawing represents a perspective view 10 of a stove, showing my design.

The leading feature of the design consists in the ornamental ring at the top, projecting outwardly from the stove-body and with lugs resting on the stove-top, a foot-rest having 15 portions extending to the legs at opposite ends of the stove, and portions extending to the body portion of the stove on a higher plane, and a draft-door having the general form of a truncated right-angled triangle in 20 cross-section, with a plate conforming to the curvature of the stove-body.

A is the body, cylindrical or oval in form.

B is the ornamental top ring, projecting outward from the stove-body and having the

lateral arms *a* resting upon the top C of the 25 stove.

D is the foot rail or rest, having curved projecting portions *d* bearing against the body of the stove and the depending curved portion *d'* extending to the legs. 30

E is the draft-door over the boxing upon which it rests, which boxing has in end elevation the general contour of a truncated right-angled triangle.

F are ornamental bands surrounding the 35 body portion near the top and bottom, and G is an ornamental urn upon the top over the fuel-opening.

What I claim as new is—

The design for a stove substantially as herein shown and described. 40

In testimony whereof I affix my signature in presence of two witnesses.

ANTON OHNEMUS.

Witnesses:

GEORGE R. SMITH,
WILFRED AMBURN.
